G. E. HAZARD,
GARAGE AIR COMPRESSOR.
APPLICATION FILED NOV. 15, 1920.

1,426,869.

Patented Aug. 22, 1922.

George E. Hazard,
By C. S. Pattison,
Attorney

UNITED STATES PATENT OFFICE.

GEORGE EDGAR HAZARD, OF ROCHESTER, NEW YORK, ASSIGNOR TO KELLOGG MANUFACTURING CO., OF ROCHESTER, NEW YORK.

GARAGE AIR COMPRESSOR.

1,426,869.

Specification of Letters Patent. Patented Aug. 22, 1922.

Application filed November 15, 1920. Serial No. 424,153.

To all whom it may concern:

Be it known that I, GEORGE E. HAZARD, a citizen of the United States, residing at Rochester, in the county of Monroe and 5 State of New York, have invented certain new and useful Improvements in Garage Air Compressors, of which the following is a specification, reference being had therein to the accompanying drawing.

10 This invention relates to improvements in garage air compressors, and is adapted to be used either as a fixed unit in the garage, or be mounted on wheels and moved around.

The primary object of my present improvement is to provide a driving gear housing having a base oil-well for lubricating the driving gears and a relatively elevated oil-supply or well receiving oil splash from the gears, to supply lubrication to the movable parts of the pump, including the piston, main bearing and connecting rod bearing.

Further objects of the invention will appear from the following description.

In the accompanying drawings:

25 Figure 1 is a vertical central section of an air-pump showing my present improvements.

30 Figure 2 is a detached sectional view, showing a modification in the construction of an oil retainer, carried by a motor shaft.

35 My improved garage compressor comprises any suitable form of electric motor 1, which is provided with a projecting drive shaft 2.

40 My improved pump construction comprises a housing having a vertical gear portion 3 and a pump portion 4, including a crank shaft case or housing 5. A suitable pump cylinder 6 is mounted on the crank case 5 and within this cylinder 6 is a suitable piston 7. Located in the housing is an elongated main pump shaft bearing 8, in which a pump shaft 9 rotates. The main shaft 9 is provided with a crank arm 10 carrying a connecting rod bearing 11, to which the lower end 12 of a connecting rod 13 is journaled, the upper end 14 of the connecting rod being suitably connected with the piston 7.

45 The bottom 15 of the crank case 5 is in a plane above the bottom 16 of the gear housing 3, the bottom of the gear housing forming a main oil supply well.

50 The end of the pump shaft 9, opposite the crank arm 10, carries a gear 17 which meshes

with a pinion 18, carried on the projecting end of the motor shaft 2.

The gear 17 dips into the main oil supply well 19 at the bottom of the gear housing 3, and the rotation of the gear splashes the oil 60 and some of it is thrown on the top of the main pump shaft bearing 8, for lubricating the shaft 9, by passing through a suitable opening or openings 20, made through the bearing, and at the same time the oil at the 65 top of the bearing 8 provides lubrication for the piston 7. The manner here shown of supplying lubrication for the piston 7, from the top of the main bearing 8, is by means of a wick 21, which rests on the top of the 70 main bearing and is connected with a lubricating pad 22, located at the bottom of the cylinder 6 in the path traveled by the piston 7. This pad 22 rests upon a baffle plate 23, which is located at the bottom of the 75 cylinder 6.

80 Preferably the top of the main bearing 8 is provided with a vertical wall 24, which forms an oil receiving well 25 on top of the main bearing and in which the lower end of the wick 21 is located. An opening 26 connects the bottom of the crank case 5, with the oil supply well 19 of the gear housing.

85 In operation, the gears splash the oil from the oil supply well 19 and some of it is thrown into or flows down the wall of the housing into the oil well 25, on top of the main bearing, and the oil passes through the opening 20 furnishing ample lubrication for the pump shaft 9, some of the oil finding its way to the crank end of the shaft for lubricating the lower end of the connecting rod and any surplus is thrown in the crank case and against the under side of the baffle plate 23, and the surplus finds its way 95 to the bottom of the crank case and flows back to the oil supply well 19, through the opening 26.

100 Attention is directed to the fact that the projecting end 2 of the motor shaft passes through an opening 27 in the gear housing and is out of contact both with the wall of the opening and an inwardly extending flange or collar 28. The shaft 2 is provided with an outwardly tapered portion 29, which terminates in a pointed flange 30 adjacent the pinion 18. By this construction oil is prevented from flowing outside of the housing without the use of a stuffing box which is usually used for this purpose. By 110

55 The end of the pump shaft 9, opposite the crank arm 10, carries a gear 17 which meshes

omitting the stuffing box I eliminate the friction of the motor shaft in such boxes, and also eliminate the necessity for any machining of the wall of the hole to receive the 5 stuffing box, and eliminate also the cost of the stuffing box.

In Fig. 2 is shown a modification of the means for preventing the splashed oil of the gear housing from running to the out- 10 side thereof by omitting the pointed flange 30 and having a taper 29' extending to the side of the pinion 18.

For the purpose of permitting access to the gear housing, its top 31 is removed 15 and held in place by suitable bolts 32.

As here shown, the gear housing 3 is made integral with a base 33 on top of which the motor 1 is suitably bolted.

I desire it to be understood that modifications and variations may be made in the 20 specific construction here shown without departing from the spirit and scope of the invention as defined in the appended claims.

By the construction here shown and de- 25 scribed, a circulation of lubricant is provided from the supply well 19, through the main shaft bearing to the crank shaft and its connecting rod bearing, the baffle plate at the bottom of the cylinder preventing the 30 oil being thrown into the cylinder to prevent excess lubrication therein, the oil falling to the bottom of the crank case and flowing back to the oil supply well 19, at the bottom of the gear housing.

35 The lubricating pad 22 at the bottom of the cylinder provides efficient lubrication for the piston and the cylinder, but prevents excess lubrication which is essential to avoid the oil mixing with the compressed air, 40 and oil thereby reaching the rubber of the tire and decomposing the rubber.

The oil level in the oil well 25 which is located at the top of the main bearing 8, is determined by the height of its wall 24, 45 which is here shown substantially on a level with the lubricating pad 22.

Having thus described my invention, what I claim and desire to secure by Letters Patent is:—

50 1. A motor driven air compressor, comprising a gear housing having an oil well at its bottom and a pump shaft bearing in combination with a crank case having its bottom above and in communication with the 55 gear case oil well, whereby the gear oil splash lubricates the main shaft bearing and any excess oil passing into the crank case flows back into the gear case oil well for the purpose of keeping the crank case dry from 60 oil.

2. A motor driven air compressor, comprising a gear housing having an oil well at its bottom and a main pump shaft bearing having an opening in communication 65 with the gear housing, in combination with

a crank case having its bottom in communication with the gear case oil well, a pump shaft, and a gear within the housing and extending into the oil well whereby the oil splash passes to the shaft bearing 70 and any excess in the crank case flows back into the gear case oil well for the purpose of keeping the crank case dry from oil.

3. An air compressor, comprising a gear case and a main pump shaft bearing in combination with a crank case, a cylinder mounted thereabove, a pump shaft in the main bearing operatively connected with a piston within the cylinder, an oil supply well at the bottom of the housing, a gear in 80 the housing and extending into the oil well and splashing oil on top of the main bearing, the pump shaft and the piston receiving lubrication only from the top of the main bearing. 85

4. A motor driven air compressor, comprising a main pump shaft bearing, a gear housing at one side thereof and a crank case at the opposite side of the bearing, the bottom of the housing having an oil supply 90 well, a cylinder mounted on the crank case, a pump shaft in the main bearing, a piston in the cylinder operatively connected with the pump shaft, a gear within the housing connected with the pump shaft and extending into the oil well, means supplied from the top of the main bearing for supplying the piston lubrication, whereby the splash from the gear oils the main shaft bearing and the piston. 95

5. A motor driven air compressor, comprising a main shaft bearing, a gear housing at one side of the bearing and a crank case at the opposite side of the bearing, an open top oil well at the top of the main bearing 105 and in communication with the main bearing, a pump shaft in the main bearing, a cylinder on the crank case, a piston in the cylinder operatively connected with the pump shaft, a gear in the housing carried 110 by the pump shaft and extending into the oil well of the housing, a cylinder and main bearing in communication with the main bearing oil well, the parts operating as described. 115

6. A motor driven air compressor, comprising a main bearing having an open top oil well on its top, a gear housing at one side of the bearing in communication with the oil well, a cylinder in communication 120 with the oil well, a piston in the cylinder, a pump shaft in the main bearing operatively connected with the piston, a gear housing having an oil supply well, a gear carried by the shaft and projecting into 125 the oil well, whereby the splash from the gear supplies oil to the main shaft oil well for lubricating the pump shaft and the piston.

7. A motor driven air compressor, com- 130

prising a main shaft bearing having an oil well at its top, a gear housing at one side of the bearing and in communication with the said oil well, a crank case at the opposite side of the main bearing, a cylinder on the crank case, a piston in the cylinder, a pump shaft operatively connected with the piston, a wick in the oil well in communication with the cylinder, a gear in the hous-

ing carried by the pump shaft, an oil well 10 in the housing into which the gear dips whereby the splash from the gear supplies oil to the main shaft oil well for oiling the main bearing and the piston through the aforesaid wick.

In testimony whereof I hereunto affix my signature.

GEORGE EDGAR HAZARD.
